UNITED STATES PATENT OFFICE.

WILLIAM L. WARD, OF ANOKA, MINNESOTA.

SNOWPLOW.

1,378,502.

Specification of Letters Patent. Patented May 17, 1921.

Application filed January 19, 1920. Serial No. 352,549.

To all whom it may concern:

Be it known that I, WILLIAM L. WARD, of Anoka, Anoka county, Minnesota, have invented certain new and useful Improvements in Snowplows, of which the following is a specification.

My invention relates to a snow plow having a flexible connection with a source of motive power which will permit the plow 10 to be raised and lowered conveniently.

The plow is used without material alteration to the truck and does not in any way interfere with the cranking of the motor or with the steering mechanism of the truck.

15 The invention consists generally in various constructions and combinations, all as hereinafter described and particularly pointed out in the claims.

In the accompanying drawings forming 20 part of the specifications,

Figure 1 is a plan view of a snow plow embodying my invention, looking at the underside thereof,

Fig. 2 is a plan view of the same, 25 Fig. 3 is a longitudinal vertical section, showing the application of the snow plow to a truck frame,

Fig. 4 is a side view of the snow plow, the forward portion of the truck being indicated in dotted lines,

Fig. 5 is a rear elevation of the plow,

Fig. 6 is a front elevation showing the manner of attaching the plow to the lifting device on the truck frame.

35 In the drawings, 2 and 3 represent the side diverging sills of the frame of the plow, having their forward ends secured and braced apart by a suitable means, such as a cross beam 4. I provide also the auxiliary 40 braces 5 and 6 between the cross brace 4 and the sills 2 and 3. 7 and 8 are top plates arranged in parallel relation with the sills 2 and 3 at the top of the plow frame. These plates are pressed and held in their proper

45 relative position by suitable supports, such as 9, 9^a, 9^b, 9^c, 9^d, 9^e, and 9^f. 11 and 11^a and 12 and 12^a are the forward and side push blocks against which the frame of the truck is seated when the plow is in use. The 50 blocks 11 and 11^a are rigidly supported by the inclined braces 13 and 13^a and blocks 10 and 10^a are horizontally mounted between the blocks 11 and 11^a and the plates 7 and 8.

55 14 is a strap, preferably of spring steel, securely bolted to the blocks 11 and 11^a and forming a rigid connection between them.

These blocks 11 and 11^a receive the forward thrust or push of the bumper on the truck as it moves forward and the plow is forced along by this pressure. The side thrust of 60 the truck is taken up by the blocks 12 and 12^a. 15 and 15^a represent chains rigidly connected to the plates 7 and 8 and 16 and 16^a represent a tackle for hoisting and lowering the plow. 17 is a suitable frame-work 65 in which the tackle-supporting mechanism is mounted on the front of the truck, being supported thereon by suitable means, such as a brace 18. 19 and 19^a represent links pivotally connected to the auxiliary braces 70 5 and 6 and also having pivotal connections with the springs 21 of the truck by suitable means, such as the clevises 22 and 22^a.

23 and 23^a represent mold-boards made of suitable sheets of metal and securely bolted 75 to the sills, plates and supports forming the frame of the plow. 24 and 24^a represent steel cutting shears, which are bolted to the lower portions of the mold-boards and to the sills 2 and 3. 25, 25^a and 25^b represent 80 shoes secured to the underside of the sills and on which the plow is supported.

In operation, the plow is pushed forward by the truck, sliding upon the shoes 25, 25^a and 25^b. The bumper of the truck contacts 85 with the forward and lateral push blocks and the plow is thereby guided and held in its proper relative position with respect to the truck, the upper part of the plow being pushed through the spring 14 while the 90 lower portion is carried forward by the thrust of the links 19 and 19^a. These links form a flexible connection between the truck and the plow and allow the convenient raising of the plow when desired. 95

It is noted in Fig. 2 that sufficient space is provided in front of the truck frame to allow the driver to stand for the purpose of cranking the motor.

I claim as my invention:

1. The combination, with a power propelled vehicle frame, of a snow plow comprising a frame having rearwardly diverging plow wings and forward and lateral push blocks mounted on said frame and having seats for the forward portion of said truck frame.

2. The combination, with a power propelled vehicle frame, of a snow plow comprising a frame having rearwardly diverging plow wings and forward and lateral push blocks mounted on said frame and hav-

ing seats for the forward portion of said truck frame, an unobstructed space being provided between said push blocks and in the rear of the apex of the plow, for the purpose specified.

3. The combination, with a truck frame, of a snow plow having diverging wings, blocks mounted in the upper portion of said plow and against which the truck frame is seated, and means flexibly connecting the lower portion of said plow with said truck for imparting a forward thrust to the lower portion of the plow.

4. The combination, with a power propelled vehicle, of a snow plow having diverging wings, the upper portion of said plow having seats thereon for the forward portion of said vehicle frame, rods pivotally connected with said truck and the lower portion of said plow for imparting a forward thrust thereto, and means mounted on the vehicle frame for lifting said plow.

5. The combination, with a power propelled vehicle, of a snow plow having diverging side wings, push blocks mounted on said plow, a flexible metallic bar secured to said push blocks and against which the forward portion of the vehicle frame is seated, and means connecting the lower portion of the plow with said vehicle frame through which a forward thrust from the vehicle is imparted to said plow.

6. The combination, with a power propelled vehicle, of a snow plow having diverging side wings, push blocks mounted in the upper portion of the frame of the plow and against which the forward portion of the vehicle frame is seated, rods having a pivotal connection with the vehicle and projecting forwardly and downwardly and pivotally connected at their forward ends with the frame of the plow for exerting a downward and forward thrust thereon when the vehicle is in motion, and means mounted on the vehicle for raising and lowering the plow.

7. The combination, with a power propelled vehicle, of a snow plow frame having diverging wings and shoes at the apex and ends of said wings and adapted to rest and slide upon the ground, said frame having a seat in its upper portion for contact with the frame of the vehicle to receive the pushing

impact thereof, and thrust rods connected with the vehicle and projecting forwardly and downwardly therefrom and pivotally connected with said frame and transmitting the forward and downward thrust from the vehicle to said frame and wings. 55

8. The combination, with a power propelled vehicle, of a snow plow frame having diverging wings and shoes at the apex and ends of said wings and adapted to rest and slide upon the ground, said frame having a seat in its upper portion for contact with the frame of the vehicle to receive the pushing impact thereof, and thrust rods connected with the vehicle and projecting forwardly and downwardly therefrom and pivotally connected with said frame and transmitting the forward and downward thrust from the vehicle to said frame and wings, a cable connected with the plow frame and a hoisting device mounted on the vehicle for raising the plow to an inoperative position. 60 65 70 75

9. The combination, with a power-propelled vehicle, of a snow-plow having diverging side wings, push blocks mounted in the upper portion of the frame of the plow and against which the forward portion of the vehicle frame is seated, rods having a pivotal connection with the springs of the vehicle at their rear ends and projecting forwardly and downwardly and pivotally connected at their forward ends with the frame of the plow for exerting a downward and forward thrust thereon when the vehicle is in motion. 80 85

10. The combination, with a power-propelled vehicle having a frame projecting in front of the traction wheels, of a snow-plow having diverging side wings and provided with a frame having seats for the forward end of said vehicle frame, said seats being near the top of the plow and the vehicle exerting a forward pushing movement thereon, and thrust rods pivotally connected at their rear ends with the frame of the vehicle and extending forwardly and downwardly therefrom and having a pivotal connection with the lower portion of the frame of the plow. 90 95 100
